UNITED STATES PATENT OFFICE.

DEXTER AVERY, OF WESTFIELD, MASSACHUSETTS, ASSIGNOR TO THE TEXTILE MANUFACTURING COMPANY, OF SAME PLACE.

CASKET TRIMMING OR ORNAMENT.

SPECIFICATION forming part of Letters Patent No. 257,455, dated May 9, 1882.

Application filed August 17, 1881. (No model.)

To all whom it may concern:

Be it known that J. DEXTER AVERY, of Westfield, in the county of Hampden and State of Massachusetts, have invented a new and useful Improved Casket Trimming or Ornament, of which the following is a specification and description.

My invention relates to that class of casket-trimmings which are made of some rigid or firm material—as wood or metal—and of spherical or curved form, and which are covered by being platted with thread or some textile material; and its object is to keep the thread or textile material together and in place as it is being applied to the rigid material, or to prevent the thread or textile material from slipping out of place either when it is applied or afterward, and I accomplish this by the means substantially as hereinafter described, and illustrated in the accompanying drawings, in which—

Figure I is a side view of a screw-knob for a casket, made according to my invention. Fig. II is a plan view of the same. Fig. III is a side view of the mold, having its surface roughened or prepared with grooves previous to being covered with the textile material, and Fig. IV is a plan view of the same.

In the manufacture of casket-trimmings of this class—those covered with a textile material and of a curved or spherical form—it has heretofore been the practice to turn or form the articles from some rigid material—as wood or metal—with a smooth surface, and afterward cover them with a textile material, usually by plating them with thread in a plating-machine; and in this process the thread slips from the smooth convex portions of the surface, and gathers into the concave portions by the action of the machine in plating, so that when the article is finished there is an excess of thread in the concave portions, while the convex portions are so imperfectly covered as to expose, in places, the surface of the wood or metal. My invention obviates all this difficulty, so that when finished an equal distribution of thread or textile material over the whole surface of the article covered is the result.

In the drawings, 2 in Fig. III represents a wooden screw-knob mold, which is provided on its convex surface with a series of grooves,

5, which grooves may be in the form of corrugations either angular or curved in their cross-section, or of any desirable form, which, in effect, will give a roughened surface to the article, so that when the thread or textile material is platted thereon, such roughened surface will prevent the thread or textile material from slipping from one part of the surface to another; and, if made of wood, these grooves or corrugations may be cut or made therein by the tool with which the article is given its general form when turned out; or, if made of metal, these corrugations may be cast therein, or the article may be made with a smooth surface and coated over with some adhesive substance—such as sizing—and then dipped into or coated over with sand, so that when dry the article shall have a rough surface. When the article is afterward platted with thread this rough surface, whether made by corrugations or grooves or sand, will prevent the thread from slipping from a convex portion to a concave portion of the surface, and after being platted or covered, the textile covering will be evenly distributed over the whole surface of the article, and will present a much better appearance than when covered upon a smooth surface, as in the ordinary manner.

If used for a screw-knob, the screw 4 may be secured in the knob 2 and used with or without a metal plate, 3, beneath the knob. Of course any other article to be used as a trimming for caskets may be treated in the same way with a roughened surface before being covered with the thread or textile material.

In this manufacture of casket-trimmings I denominate the article to be covered with the thread or textile fabric the "mold," whether made of wood or metal, or of any other sufficiently rigid or hard material.

Having thus described my invention, what I claim as new is—

An improved casket trimming or ornament, 95 consisting of a rigid mold, having its surface corrugated or roughened and platted or covered with thread or textile fabric, substantially as set forth.

DEXTER AVERY.
